INVENTOR

BY Victor J. Evans

ATTORNEY

P. J. Evans

WITNESS:

UNITED STATES PATENT OFFICE.

ULRIC C. DEIKE, OF WASHINGTON, DISTRICT OF COLUMBIA.

GOLF TEE.

Application filed March 2, 1928. Serial No. 258,653.

This invention relates to improvements in golf tees and supporting and anchoring means therefor, an object being to provide a tee which will remain in position to support a ball in proper driving position, and which in the event of being struck by a club, will not act to check the swing and will, in the majority of cases, remain anchored to the ground.

10 Another object of the invention is the provision of a tee which in addition to the above and other advantageous features, is simple and efficient in use, and may be manufactured and sold at a low cost.

15 With the above and other objects in view, the invention further includes the following novel features and details of construction, to be hereinafter more fully described, illustrated in the accompanying drawing and pointed out in the appended claims.

In the drawing:—

Figure 1 is a view partly in elevation and partly in section illustrating the invention in use.

25 Figure 2 is a view showing the position of the tee after the drive.

Figure 3 is a view similar to Figure 1 showing a slightly modified form of the invention.

Figure 4 is a view at right angles to Figure 3.

Figures 5 and 6 are elevations of another form of the invention.

Figure 7 is a view of still another form.

Referring to the drawing in detail and especially to Figures 1 and 2, the reference character 10 indicates the body of the tee which is provided at one end with a depression or seat 11 to receive a golf ball 12. The opposite end of the body 10 has secured there-

40 to an anchoring means, which, as shown in Figures 1 and 2 consists of a penetrating pin. This pin is substantially U shaped and includes spaced legs 13 and a connecting bar 14, the latter passing through an opening pro-

45 vided in the body 10 so that the body and anchoring means are pivotally connected. The lower end of the body is oppositely beveled so as to provide a more or less pointed extremity 14 which is adapted to penetrate the

50 ground and yieldingly hold the body against independent pivotal movement.

In the use of the invention should the club strike the tee or body 10, the body will oc-

cupy the position shown in Figure 2 of the drawing which will permit of an unobstructed swing of the club without pulling the tee from the ground. Danger of loss of the tee is thus practically eliminated and as the construction is such that it will not be readily broken, the tee will last for a relatively long period.

In the form of the tee shown in Figures 3 and 4, the body 10^a is substantially L shaped and has its offset portion provided with a seat 11^a for the ball 12. The anchoring pin 14 is indicated at 14 and is pivotally connected to the body as shown at 15. The body is provided at its lower end with an extension 16 which is adapted to enter the ground in the manner explained in connection with Figures 1 and 2 so as to hold the body in position to support the ball. When the ball is struck, the offset or ball receiving portion of the body will bury itself in the ground so that no obstruction will be offered to the club.

In Figures 5 and 6 the offset portion 17 of the body 10^b is pivotally mounted as shown at 18 so that when struck by a club, the body including the offset portion 17 will flatten itself upon the surface of the ground.

The tee shown in Figure 7 comprises a penetrating member or support 19 from which extends bristles 20. These bristles are arranged to provide a concavity or seat at their upper ends so as to receive the ball 12. The tee is inserted so that the lower ends of the bristles are positioned beneath the surface of the ground which acts to stiffen and hold them in proper position to support the ball. When struck by a club however these bristles will readily flex.

The invention is susceptible of various changes in its form, proportions and minor details of construction and the right is herein reserved to make such changes as properly fall within the scope of the appended claims.

Having described the invention what is claimed is:—

1. In a golf tee, a body having a ball receiving depression in one end, ground engaging anchoring means, means pivotally connecting the body and anchoring means, and means carried by the body below the pivotal connection to engage the ground and resist independent movement of said body.

2. In a golf tee, a body having a ball re-

ceiving depression in one end, a ground penetrating extremity at its opposite end, and anchoring means pivotally connected with the body above the penetrating extremity and adapted for insertion into the ground.

3. In a golf tee, a body having a ball receiving depression in one end, a ground penetrat-

ing extremity at its opposite end, and a substantially U-shaped penetrating pin pivotally connected with the body above the penetrating extremity and adapted for insertion into the ground.

In testimony whereof I affix my signature.

ULRIC C. DEIKE.
